17 Claims. (Cl. 28—46)

1

In the weaving of textile fabrics the warp threads are passed through heddles arranged in frames called harnesses. By raising and lowering the harnesses alternately the threads engaged by the heddles are simultaneously raised and lowered. In this manner there is produced a shed in the thread layer, through which shed a shuttle carrying the weft thread is passed during the weaving process.

The passing of the threads through the heddles has hitherto been effectuated by an operator extracting a thread from the thread layer that is wound on a beam, and holding this thread towards the heddle, whereupon another operator by means of a heddle hook draws the thread through the eye of the heddle.

Prior to this, the weaving diagram is produced on a drawing that indicates the sequence in which the threads are to be passed through the heddles. The operator who is to select the heddles must therefore for every thread look at the diagram and count the harnesses from one end in order to ascertain the position of the heddle required. In simple patterns the sequence may be learned by heart, but this is not possible if the pattern is complicated and perhaps interrupted by periodical variations. In such instances the proceeding will be slow, as a study of the drawing is necessary for every thread, because in case a thread is passed through a wrong heddle it will be necessary to remove all subsequent threads and pass them through their correct heddles according to the diagram. This causes a great waste of time.

To provide a quicker and more exact selection of harnesses and heddles a mechanical and automatic method has been proposed for indicating the harness carrying the heddle through which a certain thread is to be passed. This method consists in the harness in question being raised somewhat in relation to the other harnesses. The raising of the harness may be brought about manually or otherwise.

This raising of the harnesses is, however, not practical, because it requires not alone a comparatively great consumption of power which is tiring, because the operation is repeated thousands of times, but the continual movement up and down of the harnesses and heddles produces a flickering before the eyes of the operator which is exceedingly disturbing and tiring and causes uncertainty in the selection of the harnesses or the heddles. Likewise the continual movement up and down of the heddles brings about dis-

2

order among the threads already passed through the heddle eyes.

In order to improve upon this method it has been proposed that instead of raising the harnesses for indication purposes there are employed light threads, cords, bands, or rods, disposed longitudinally to the harnesses and crosswise to the heddles, and which are raised and lowered to indicate the harness in question. This raising and lowering is brought about by means of a jacquard mechanism in which the said members are suspended. In this manner the power consumption is reduced and the method accordingly less tiring, but it still requires the employment of a jacquard mechanism, and there is still a constant movement up and down of the indicating members with a resultant flickering which is disturbing and tiring. Furthermore the indicating members employed form a net-work above the eyes of the heddles which to some extent obscures the view of the heddles and complicates the selection of the correct heddle.

The present invention relates to a device for selecting heddles for the application of threads, in which device the heddles are indicated in a sequence corresponding to a weaving diagram, and in which device there are indicating members which in a predetermined sequence by a manual preliminary movement automatically by electrical means provide a visible indication, partly of the heddles, or of the harnesses carrying the heddles which at any time are to be selected, and partly if desired of the thread layer of the beams from which the thread in question is to be extracted.

This device offers the advantage that only a minimum of manual labor is required, and there does not occur any up and downward movement of the harnesses or heddles, or of any special indicating members, for which reason disturbing flickering as formerly known is eliminated, and the operation is not disturbing or tiring to the operator.

The invention is illustrated in the accompanying drawings, in which Fig. 1 is a perspective view of a treadle-operated circuit closer which may be used in connection with the device shown in Fig. 2.

Fig. 2 is a schematic perspective view, partly in section, of one form of device embodying the invention and in which there are employed signal lamps as indicating means.

The device illustrated in the drawing has only four harnesses with apertaining heddles. In the drawing only the lower part of each of the harnesses 1 is visible. The upper parts of the

harnesses are omitted for the sake of distinctiveness.

The heddles 2, the upper portions of which are not visible in the drawings, are arranged slidably along rods 3 disposed rigidly in the end portions of the harnesses. In the drawing only a portion of the lower rods 3 are visible. The heddles 2 have each an eye 4 in their middle.

The thread layers 5 and 6 are wound on beams 7 and 8 respectively, from which the threads supplied to the heddles may be taken, but threads may be taken from only the one layer as illustrated, or there may be more than two thread layers, from which threads are taken.

In the manner of construction illustrated the device consists of indicating members in the form of signal lamps that are lighted and extinguished, and which operations are performed by means of the heddles through the eyes of which threads are to be passed in accordance with the weaving diagram. Direct light may be employed, in which instance the signal members may be placed close to the heddles, or if there is insufficient room for the signal members close to the heddles the direct light may be so arranged that the light is for instance reflected through a hollow member provided with a slit facing the heddles. Reflecting light may likewise be employed, for instance as indicated in the drawing, where the signal lamp 22 is placed beneath the harness 1 within a holder 23 that has an extension 24 made of transparent material as for instance glass, or a translucent material as Celluloid. The extension 24 is so formed that it may be placed between the harnesses 1, and may extend up to the heddle 2. The light from the signal lamp will issue through the extension and be reflected from the upper end thereof. To obtain an improved signal light the lamps may be colored. Signal lamps for either direct, indirect, or reflected light through the members 24, may be arranged in front of or in rear of or both in front and in rear of the heddles. In the latter instance the lamps are lighted in pairs.

There may likewise be arranged signal lights for indicating the thread layers 5 and 6 or the thread beams 7 and 8. Such signal lamps are indicated by 25 and 26 respectively. There may likewise be employed direct, indirect, or reflected light in the same manner as described in connection with the heddles.

The signal lamps 22, the holders 23, and the extensions 24 are disposed movably across the thread layer on any suitable support (not shown) so that the signal lights are always close to the heddles through the eyes of which threads are to be passed. Upon reference to Fig. 2 it will be seen that the lamp holders 23 are connected by a forwardly and rearwardly extending bar under the bottom bars of the harnesses, said bar being suitably supported for movement lengthwise of the harnesses.

The signals produced by the signal lamps 22 are obtained by means of a rotary, electric circuit controller which may take a form of a contact drum 27 with contact points 28, the drum being rotated intermittently by means of a pawl wheel 29 rigidly attached to the drum, and a pawl 30 coacting with the pawl wheel 29. The pawl 30 is for instance operated by means of an electromagnet 34 that receives current through a contact device 138 and 139 operated by a treadle 17 shown in Fig. 1 or any manually-actuated means. The contact points 28 are arranged in such a manner on the drum 27 that during the rota-

tion of the drum the signal lamps are lighted in the sequence determined by the weaving diagram.

The contact points 28 on the drum 27 may for instance be obtained by the drum being made of electrically conductive material, over which there is placed an interchangeable endless band of electrically non-conductive material, which band has apertures through which contact fingers 31 may be brought into conductive contact with the drum surface in a predetermined sequence.

The current for the signal lamps is taken from from a suitable source of current 32, and is distributed through a suitable wiring 33. If desired the circuit through the wiring 33 may be opened and closed by the treadle-operated switch shown in Fig. 1 in which 17 is a pivoted treadle carrying contact 138 to engage a suitably supported coacting contact 139, the wires 33 being run to said contacts.

Instead of operating the signal lights by a tilting means such as the treadle 17 the operation may be brought about by the operator actuating an electric contact for every thread to be passed through the eye of a heddle, thereby supplying current to the electromagnet 34 that operates the pawl mechanism 30, 29 give the drum a step-by-step rotary movement. This electric contact device may for instance be omitted by a heddle hook 35 being suspended in a telescopic rod 36 arranged to swing on a pin 37. The rod 36 has a contact arm 38 which by swinging the rod coacts with a contact member 39 for closing the circuit through the electromagnet 34. Any other suitable manually-actuated switch may be used to control the circuit through the coil of the electrical device 34.

Instead of the rod 36 and the contact members 38 and 39, the heddle hook may be electrically connected to the wiring 33, and behind the heddles 2 there may be placed contact rails by means of which the circuit through the electromagnet 34 is closed, when a heddle hook is inserted through the eye of a heddle and contacts the rail behind the heddle. Such contact rails are not included in the drawing.

In connection with the pawl mechanism 30, 29, or the core of the electromagnet 34, there may be arranged members that interrupt the circuit to the contact drum during its rotational movement. Furthermore there may in connection with the pawl mechanism 30, 29, or with the core of the electromagnet 34, be arranged a member 40 that during the rotation of the drum raises the contact fingers 31 out of engagement with the drum surface.

I claim:

1. In a device for selecting heddles in a sequence corresponding to a predetermined weaving diagram, the combination with a loom having a series of parallel harnesses carrying heddles to be threaded, of illuminating indicating members, each including an electric signal lamp, there being one member associated with each of the harnesses, means for holding said members in close relation to the harnesses to illuminate the heddles thereof, a rotary, electric circuit controller for illuminating said lamps in a predetermined sequence, an electric circuit including said controller and said signal lamps, electrically-operated means for giving said controller a step-by-step rotary movement, a manually-actuated switch, and a second electric circuit including said switch and said electrically-operated means.

2. The combination of claim 1 in which said holding means connects all of said indicating

members and is movable lengthwise of the harnesses to illuminate various heddles thereof.

3. The combination of claim 1 together with means for interrupting the circuit of said signal lamps when said rotary circuit controller is rotated.

4. In a device for selecting heddles in a sequence corresponding to a predetermined weaving diagram, the combination with a loom having parallel harnesses carrying heddles to be threaded, and beams carrying the thread layers supplying threads to the heddles, of a plurality of illuminating indicating members, each including an electric signal lamp, there being one member associated with each of the harnesses, means for holding said members in close relation to the harnesses to illuminate the heddles thereof, a second plurality of illuminating indicating members, each of the latter being associated with one of said beams and including an electric signal lamp, a rotary, electric-circuit controller for illuminating the lamps of both of said pluralities of indicating members in a predetermined sequence, an electric circuit including said controller and all of said signal lamps, electrically-operated means for giving said controller a step-by-step rotary movement, a manually-actuated switch, and a second electric circuit including said switch and said electrically-operated means.

5. The combination of claim 4, together with means for interrupting the circuit of all of said signal lamps when said rotary circuit controller is rotated.

6. In a device for selecting heddles in a sequence corresponding to a predetermined weaving diagram, the combination with a loom having a series of parallel harnesses carrying heddles to be threaded, of an electric signal lamp for each of the harnesses positioned adjacent the bottoms of the harnesses, holding means connecting all of said lamps and extending in a forward and rearward direction under the bottoms of all of the harnesses, a rotary, electric-circuit controller for illuminating said lamps in a predetermined sequence, an electric circuit including said controller and said lamps, electrically-operated means for intermittently rotating said controller, a manually-actuated switch and a second electric circuit including said switch and said electrically-operated means.

7. The combination of claim 6 together with upright light-directing extensions on said holding means and associated with each of said lamps, said extension projecting above the bottoms of the harnesses to illuminate the heddles of the respective harnesses.

8. The combination of claim 6 in which said holding means is movable longitudinally of the harnesses.

9. In a device for selecting heddles in a sequence corresponding to a predetermined weaving diagram, the combination of illuminating indicating members, means for holding the indicating members in close relation to the parts to be selected, rotatable electric contact members for actuating the indicating members in a predetermined sequence, means for electrically actuating the said rotatable members to rotation, an electric circuit, a contact device included in this circuit, a telescopic rod attached to the one contact member for actuating it to movement in relation to the other contact member of the contact device, and a heddle hook attached to the free end of the telescopic rod.

10. In a device for selecting heddles in a se-

quence corresponding to a predetermined weaving diagram, the combination with a loom having parallel harnesses carrying heddles to be threaded, of an electric signal lamp associated with each of the harnesses, holding means connecting all of said lamps for holding them in close relation to the harnesses to be selected, said holding means being movable lengthwise of the harnesses, a rotatable contact drum, electrically operated means for actuating the said drum to rotation, an electric circuit including the drum surface, the signal lamps, and contact fingers corresponding in number to the signal lamps, a nonconductive sheet inserted between the drum surface and the contact fingers and having perforations for producing electric contact between the said contact fingers and the drum surface in a predetermined sequence for lighting the signal lamps, a contact device included in the circuit, and manually-actuated means for actuating the said contact device.

11. In a device for selecting heddles in a sequence corresponding to a predetermined weaving diagram, the combination with a loom having parallel harnesses carrying heddles to be threaded, of an electric signal lamp associated with each of the harnesses, holding means connecting all of said lamps for holding them in close relation to the harnesses to be selected, said holding means being movable lengthwise of the harnesses, a rotatable contact drum, electrically operated means for actuating the drum to rotation, an electric circuit including the drum surface, the signal lamps, and contact fingers corresponding in number to the signal lamps, a nonconductive sheet inserted between the drum surface and the contact fingers and having perforations for producing electric contact in a predetermined sequence for lighting the signal lamps, means for reflecting the signal light on the heddles of the harness to be selected, a contact device included in the circuit, and manually-actuated means for actuating the said contact device.

12. In a device for selecting heddles in a sequence corresponding to a predetermined weaving diagram, the combination with a loom having parallel harnesses carrying heddles to be threaded, of an electric signal lamp associated with each of the harnesses and disposed adjacent the lower bars thereof, movable holding means connecting all of said lamps for holding them in close relation to the heddles to be selected, light-directing extensions carried by said holding means and associated with said lamps, said extensions projecting upwardly above the bottoms of the lower bars of the harnesses to direct light from said lamps upon the heddles, a rotatable contact drum, electrically-operated means for actuating the drum to rotation, an electric circuit including the drum surface, the signal lamps and a number of contact fingers, a nonconductive sheet inserted between the drum surface and contact fingers and having perforations for producing electric contact between the drum surface and the contact fingers in a predetermined sequence for lighting the signal lamps, a contact device included in the circuit, and manually-actuated means for actuating the said contact device.

13. In a device for selecting heddles in a sequence corresponding to a predetermined weaving diagram, the combination with a loom having parallel harnesses carrying heddles to be threaded, of an illuminating indicating member associated with each of the harnesses, movable

holding means connecting all of said members and movable with respect to the harnesses to positions in which the indicating members are in close relation to the heddles to be selected, rotatable means for illuminating said indicating members in a predetermined sequence, electrically-operated means for actuating said rotatable means, and electric contact members for controlling said electrically-operated means.

14. In a device for selecting heddles in a sequence corresponding to a predetermined weaving diagram, the combination of electric signal lamps, means for holding the lamps in close relation to the parts to be selected, a rotatable contact drum, electrically operated means for actuating the drum to intermittent rotation, an electric circuit including the drum surface, the signal lamps, and contact fingers in a number corresponding to the number of lamps, a non-conductive sheet inserted between the drum surface and the contact fingers and having perforations for producing electric contact between the drum surface and the contact fingers in a predetermined sequence for lighting the signal lamps, means for interrupting the circuit during the intermittent movement of rotation of the drum, a contact device included in the said circuit, and manually-actuated means for actuating the said contact device.

15. In a device for selecting heddles in a sequence corresponding to a predetermined weaving diagram, the combination of electric signal lamps, means for holding the lamps in close relation to the parts to be selected, a rotatable contact drum, electrically operated means for actuating the drum to intermittent rotation, an electric circuit including the drum surface, the signal lamps and contact fingers, a nonconductive sheet inserted between the drum surface and the contact fingers and having perforations for producing electric contact between the drum surface and the contact fingers in a predetermined sequence, means for raising the contact fingers out of engagement with the said sheet during the

intermittent rotation of the drum, a contact device included in the said circuit, and manually-actuated means for actuating the said contact device.

- 5 16. In a device for selecting heddles in a loom in a sequence corresponding to a predetermined weaving diagram, the combination within the loom, of indicating members disposed at the front and the back of each heddle to be selected, means 10 for holding the indicating members in close relation to the said heddles, rotatable members for actuating the indicating members in pairs in a predetermined sequence, electrically-operated means for actuating the said rotatable members 15 to rotation, and contact members for controlling the said electrically operated means.
17. In a device for selecting heddles in a sequence corresponding to a predetermined weaving diagram, the combination of harnesses carrying 20 heddles, beams to hold thread layers to supply threads to the heddles, two groups of indicating members, means for holding one group of these members in close relation to the heddles to be selected, and another group in relation to the beams carrying the thread layers, rotatable electric contact members for actuating both groups of indicating members in predetermined sequences, electrically operated means for actuating said rotatable electric contact members 25 to rotation, contact means for controlling the said electrically operated means, and manually-actuated means for actuating the said contact members.

35 SVEND SIGURD CHRISTIE FLEISCHER.
